BAND BRAKE

Filed Oct. 19, 1925

Inventor
Melvin Stringer.

By his Attorney
Thomas A. Hill.

UNITED STATES PATENT OFFICE.

MELVIN STRINGER, OF NEW YORK, N. Y.

BAND BRAKE.

Application filed October 19, 1925. Serial No. 63,234.

My invention relates to improvements in band brakes, and more particularly has reference to and is illustrated in the accompanying drawings in its application to a split band brake, which may be an internal band, such as are commonly used in automobiles and is in the nature of a modification of my co-pending application S. N. 734,935.

10 According to a preferred embodiment of my invention, the brake is operated at the split or opening in the band in such a manner that the trailing side or end of the band is advanced over the opposing side in applying the brake, so as to apply the band more uniformly to the drum throughout its length, thereby increasing its efficiency and braking power.

15 In the accompanying drawings, I have illustrated in Fig. 1 in perspective a suitable form of band brake embodying an application of my invention. Fig. 2 is a similar view illustrating a modification. Fig. 3 is a broken section illustrating the arrangement 20 of the separating strips.

25 1 indicates a steel band which is split or separated at the ends as indicated at 2 and which is provided with a suitable bearing or support 3.

30 In Fig. 2 a two-part reinforcing web 4 and 5 is shown and may be used, the same preferably being secured to the band by separating strips as shown at 6 and 7 indicates a spring across the split of the band. 35 8 and 9 indicate links pivotally mounted as shown in the toggle 10, said toggle being suitably secured to the usual pin 11 for rotating the same.

The link and toggle pins 12, 13 are usually 40 mounted equally distant from the center of rotation of the toggle 10, but according to the preferred embodiment of my invention, and assuming that the vehicle is traveling from left to right, looking at the drawing, 45 the pin or bearing 12 is at a slightly greater distance from the center 11 than the pin or bearing 13. This causes the end of the band pointing in the direction of rotation of the wheel to expand less rapidly or to less extent

than the opposite end which extends in a direction opposite to the direction of the rotation of the wheel, and by this compensation the heretofore uneven wear of the brake lining is overcome and the application of the band pressure is more uniformly applied 50 around the circumference of the drum, thereby increasing the brake efficiency.

55 In place of the toggle, other means may be employed for opening the band, such for instance as the cam 10' shown in Fig. 2 and in such case the adjacent ends of the band may be turned in and backed by the webs 4 and 5 as shown. Also in the modification shown in Fig. 2, the ends of the spring 7 may be secured in the reinforcing webs as 60 shown instead of to the link bearings 14, 15 shown in Fig. 1.

65 Referring more particularly to Fig. 3, it will be seen that the separating strips 6 are spot welded to the inside of the band 1, and to the periphery of the reinforcing piece 4, as shown at 16, 17, leaving a space between 70 said pieces and said band.

75 Of course it will be understood that various modifications may be made in the construction and arrangement of parts without departing from the spirit of the invention as claimed.

I claim:

1. In a band brake of the class described, 80 a substantially flat steel band, and substantially flat steel reinforcing webs substantially at right angles thereto and at the center of one side thereof, said webs separated from said band providing a space therebetween.

85 2. In a band brake of the class described, a substantially flat steel band, and substantially flat steel reinforcing webs substantially at right angles thereto and at the center of one side thereof, said webs separated from said band providing a space therebetween and said webs secured to said band.

90 3. In a band brake of the class described, a substantially flat steel band, and a two-part substantially flat steel reinforcing web substantially at right angles thereto, said band turned in at the ends thereof and said

web abutting said turned-in ends and separating pieces between said web and said band.

4. In a band brake of the class described, 5 a substantially flat steel band, and a substantially flat two-part steel reinforcing web substantially at right angles thereto, said band turned in at the ends thereof and two

of the ends of said web abutting said turned-in ends and a spring adjacent the ends of 10 said band and anchored to said webs and separating pieces between said web and said band.

In testimony whereof I hereunto affix my signature.

MELVIN STRINGER.
